[57] **CLAIM**

The ornamental design for a cart, as shown and described.

DESCRIPTION

FIG. 1 is a perspective view of a cart showing our new design, looking down on the left-hand side;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof.

The broken lines in the drawings are for illustrative purposes only.
